ATTORNEY.

UNITED STATES PATENT OFFICE

WILLIAM A. MARTIN, OF TRENTON, MISSOURI

MAUSOLEUM

Application filed June 6, 1932. Serial No. 615,531.

My invention relates to mausoleums and more particularly to burial vaults formed of concrete or similar material for indefinitely preserving a corpse.

Although numerous vaults including a dead air chamber above the casket compartment and covered with poured cement to complete sealing of the casket and dead air chambers have been devised for this purpose, those of which I am aware do not embody provisions for positively preventing water, present in the poured cement, from passing downwardly into the casket chamber.

While the amount of water necessary to mix the final layer of sealing cement is not great, it is sufficient to maintain the dead air and casket chambers in moistened condition throughout a relatively long period of time, particularly since it will be impossible for the water, after passing into these chambers, to escape therefrom.

It is the principal object of my invention, therefore, to so construct a vault that the water in the sealing cement can readily escape to the exterior of the vault.

A further object of the invention is to provide separate sealed joints for the casket and dead air chambers to further insure against seepage of moisture into the casket compartment.

In accomplishing these and other objects of my invention, I have provided improved details of structure, the preferred form of which is illustrated in the accompanying drawing, wherein:

Fig. 1 is a longitudinal central section through the vault illustrating the arrangement of the inside covers to produce independently sealed casket and dead air chambers.

Fig. 2 is a cross section of the vault on the line 2-2, Fig. 1.

Fig. 3 is an enlarged fragmentary sectional view showing particularly the man-

ner of sealing the joints between the inside covers and the offset shoulders of the containers.

Referring more in detail to the drawing:

1 designates a container of reinforced waterproof concrete, or the like, embedded in earth 2 and including a bottom or floor 3, side walls 4 and end walls 5. To maintain a casket in elevated condition above the floor of the container, a plurality of transverse bars 6 are preferably formed on the bottom wall 3.

The side and end walls are interiorly offset at vertically spaced points to produce upwardly facing lower and upper peripheral shoulders 7 and 8 spaced slightly from each other and located somewhat above a horizontal median line of the container.

A lower inside cover 9, preferably of arched formation and cast of reinforced concrete or similar material, is adapted to rest on the lower shoulder 7 to divide the lower portion of the container into a casket chamber 10 and the upper outer edge of the cover is beveled, as indicated at 11, so that a suitable sealing compound 12 may be plastered into the peripheral cavity formed by the beveled edge and surrounding container wall for sealing the casket chamber.

An upper inside cover 13, also preferably cast of reinforced concrete, or the like, is adapted to seat on the upper shoulder 8 to produce a dead air chamber 14 above the casket chamber, and is arched with its side and end edges, comprising flanges 15 and 16 diverging abruptly downwardly toward the inner surface of the container to seat in sealing compound 17 preferably provided on the shoulder 8.

Handles or grips 18 may be cast on the upper surfaces of both the lower and upper inside covers to facilitate handling of the cover members.

Formed on the outer surface of the container adjacent its upper end is an upward-

ly facing peripheral seat or shoulder 19 for supporting an upper outside cover or top 20 having a depending flange 21 adapted to seat on the shoulder 19.

5 As is particularly illustrated in Fig. 3, and indicated at 22, the inner surface of the flange is spaced from the container, and the depending flange 21 is of sufficient height to reserve a slight clearance 23 between the 10 upper edge of the container and the outside cover for a purpose presently described.

The top is also slightly arched and cast thereon near one end thereof is an elevation 24 having a gradually inclined face 25 provided with a recess 26 for receiving an inscription plate 27, as in similar vault covers.

After placing the lower and upper inside covers on the respective flanges 7 and 8, the portion of the container above the upper 20 cover is filled with a body of waterproof cement 28, or equivalent sealing material, and it is for the purpose of permitting escape of the water used in mixing the cement and rising to the upper surface of the body 25 as the sealing material sets, that the cement is filled in the container to a common level with the upper edge of the container and that the spaces 22 and 23 are provided between the outside cover and container.

30 To further insure flow of this water over the upper edges of the container, the body of sealing material is raised along its longitudinal median line as indicated at 29 and is sloped downwardly from each side of the 35 line toward the upper edge of the container.

Assuming vault members to be constructed as described, the order and procedure of assembly of the members for interment of a corpse is as follows:

40 After providing a suitable excavation for the container and lowering the container therein, the casket is let down to rest on the cross members 6. The lower inside cover is then seated on the lower shoulder 7 and 45 sealing compound is plastered around its margin to prevent penetration of moisture into the casket chamber. A layer of sealing compound is next positioned on the shoulder 8 and the upper inside cover is mounted 50 thereon to produce a sealed dead air chamber between the lower and upper inside covers.

The remaining portion of the container is then filled with waterproof cement to an 55 elevation slightly above the upper edge of the container and the upper surface of the cement body is tapered downwardly toward each of the side walls of the container to direct water from the cement outwardly toward the container walls.

For the final step, the top is mounted over the container and seated on the shoulder 19.

As the body of cement begins to set, water used in mixing the material will rise to the 65 surface of the body, flow down the sloping

top thereof and over the upper edge of the container through the clearance 23 and space 22.

Since the outside cover is merely seated on the shoulder 19, moisture can escape outwardly through this joint into the earth. It will, however, be impossible for moisture to enter in like manner into the container since the space between the sealing body and outside cover is filled with trapped air so 75 that the lid comprises in effect an automatic sealing top for the container.

While I have shown the vault imbedded in the earth, it is obvious that it is equally as effective when mounted on or above the 80 earth.

What I claim and desire to secure by Letters Patent is:

1. A vault including a container having a vertical peripheral wall provided with an 85 upwardly facing shoulder, an inside cover adapted to rest on said shoulder, a layer of sealing cement on said cover having its entire upper surface extending to a level for draining liquid rising in the cement 90 over the upper edge of said wall, and a top for the container.

2. A vault including a container having a vertical peripheral wall provided with upwardly facing interior and exterior shoulders, an inside cover adapted to rest on the interior shoulder, a layer of sealing cement on said cover extending throughout its area to a common level with the upper edge of said wall for draining liquid rising in the 100 cement over said edge of the wall, and a top having a depending flange spaced from the container and adapted to rest on the exterior shoulder.

3. A vault including a container having a vertical peripheral wall provided with an upwardly facing interior shoulder, an inside cover adapted to rest on said shoulder, a layer of sealing cement on said cover having a raised upper surface sloping downwardly 110 to the upper edge of said wall and to a common level with said edge for draining liquid rising in the cement over said edge of the wall, and a top for the container.

4. A vault including a container having a vertical peripheral wall provided on its interior surface with spaced upwardly facing shoulders, a lower inside cover resting on the lower shoulder to form a casket chamber, sealing means between the cover and said shoulder, an upper inside on the upper shoulder forming a dead air chamber between said covers, a layer of sealing cement on the upper cover having its entire upper surface raised to a level for draining liquid rising in the cement over the upper edge of said wall, and a top for the container.

5. A vault including a container having a vertical peripheral wall provided on its in-

terior surface with vertically spaced upwardly facing shoulders, a cover resting on the lower shoulder, a cover resting on the upper shoulder, sealing means between the 5 covers and their respective shoulders, a layer of sealing cement on the upper cover having its upper surface level with the upper edge of said wall, and a top for the container.

6. A vault including a container having 10 a peripheral wall provided with vertically spaced upwardly facing interior shoulders and with an exterior shoulder, a cover resting on the lower interior shoulder, a cover resting on the upper interior shoulder, sealing 15 means between the covers and their respective shoulders, a layer of sealing cement on the upper cover having a raised upper surface sloping downwardly to the upper edge of said wall and to a common level with 20 said edge for draining liquid rising in the cement over said edge of the wall, and a top having a depending flange spaced from the container and adapted to rest on said exterior shoulder for spacing the top above 25 the upper edge of the container wall for permitting escape of said liquid from the vault.

In testimony whereof I affix my signature.

WILLIAM A. MARTIN.
